UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,387,111.

Specification of Letters Patent. Patented Aug. 9, 1921.

Application filed January 16, 1920. Serial No. 351,776.

To all whom it may concern:

Be it known that I, FRED S. CARR, a citizen of the United States, and a resident of Newton, in the county of Middlesex, Commonwealth of Massachusetts, have invented an Improvement in Fasteners, of which the following description, in connection with the accompanying drawings, is a specification, like characters on the drawings representing like parts.

This invention pertains to improvements in separable fasteners of the type wherein a stud member is adapted to engage with a socket member carrying stud-engaging jaw means.

The preferred form of my invention shown in the drawings of the present application provides a fastener in which the tendency to become disengaged under lateral strain is minimized, while at the same time permitting the facile disengagement of the parts when separating strain is exerted in any direction which does not provide a substantial resultant force exerted in a lateral direction.

In the drawings of the present invention I have shown a preferred embodiment of my invention resembling somewhat the fastener shown in my pending application Serial No. 307,111, filed June 27, 1919.

In the drawings:—

Figure 1 is a front elevation of two pieces of material held together by an illustrative embodiment of a preferred form of my invention, parts of the fastener being shown in dotted lines;

Fig. 2 is a section on the line 2—2 of Fig. 1;

Fig. 3 is a view showing several fasteners applied to two pieces of material to be held together;

Fig. 4 is a view of a preferred form of socket, taken from the side thereof where the spring is exposed; and

Fig. 5 is a section on the line 5—5 of Fig. 4.

I have found in practice that where the form of fastener shown in my copending application above referred to is correctly applied to the material, so that the line of lateral strain between stud and socket tends to move the stud in the socket toward one of the notched ends of the socket, a very secure lock is provided. The fastener shown in my copending application works satis-

factorily, even where the line of strain between stud and socket is at a considerable angle from that which would tend to move the stud directly toward one of the notched openings. When, however, the socket is accidentally applied to the material in such a way that the line of strain between stud and socket is exactly or substantially exactly ninety degrees from the notched portion of the socket aperture, the strain being exactly perpendicular to the adjacent spring portion, the fastener shown in my copending application above referred to does not operate any better than any ordinary snap fastener in which separation is readily effected by any considerable strain in a lateral direction.

I have found by experiment that by positioning the spring means in such a way as to be at an angle to a line passed through the center of the socket aperture and the center of a coöperating notch inside thereof, a construction is afforded in which a very substantial lateral locking is provided against separation of stud and socket by strain in any lateral direction. In the preferred form of my invention shown in the drawings, this result is attained because, where strain is exerted between stud and socket in a direction exactly perpendicular to an adjacent spring portion, such strain cannot be exactly perpendicular to a line passed through the center of a notch at the center of the aperture. Similarly, where strain between stud and socket is exerted in a direction exactly perpendicular to a line between the center of the notch and the center of the aperture, such strain cannot be perpendicular to the adjacent spring portion and therefore there is a tendency for the stud to be moved toward an adjacent notch, the spring portion acting as a cam surface to promote such movement. The foregoing improved operation is particularly noticeable where the fasteners are applied to fabric, providing a non-rigid support for the stud and socket.

I have also found that the location of the spring means on a diagonal, as shown in the present application, greatly reduces the strain on the spring where strain is exerted in a direction substantially or exactly perpendicular to the spring portion acted upon under such a strain. This is because the amount which the stud can move

the spring under such a strain before the neck of the stud strikes the socket casing is greatly reduced.

In the preferred form of my invention shown in the drawings, 6 represents a piece of fabric to which a stud 7 is secured, and 8 represents a piece of fabric to which a socket 9 is secured. The stud 7 may be of usual form providing a head, a neck and an attaching portion which can be sewed to the goods. The socket also may be adapted to be sewn to the goods in any usual manner. The socket shown in the drawings provides at one side a disk having an aperture there-through which is preferably notched at opposite ends, as shown in my copending application above referred to, and having spring means herein typified by the V-shaped spring 10 providing two spring portions adjacent the aperture which are at an angle to a line passed through the center of a notch and the center of the aperture. The notches are preferably so proportioned that the neck of the stud cannot touch the marginal portion of the notch at the end thereof, the bearing being at the side of the notch and the notches being proportioned so that the neck of the stud cannot enter into the notch a sufficient distance to oppose substantial strain exerted on stud and socket to separate them, which strain is at a substantial angle from any angle which is likely to result from lateral strain on the fabric to which the stud and socket are applied.

The socket illustrated in the present application is of the type which may be applied to the goods either side up. When the socket is applied to the goods as shown in Fig. 2 with the side thereof having the stud-receiving aperture outwardly, the fastener is a lateral lock fastener. When, however, the socket is applied to the goods with the side having the aperture next to the material and the stud entering from the opposite side, then the fastener is preferably not adapted to lock under lateral strain. This feature of my invention is, however, applicable to many constructions in which the spring arrangement may differ materially from that hereinbefore described, and for this reason I have elected to make claims to this feature in a copending application filed herewith, Serial No. 351,777, filed Jan'y 16, 1920.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

Claims:

1. A fastener comprising, in combination, a stud having a head and a neck, and a socket providing at one side thereof a stud-receiving aperture providing a relatively shallow notch at at least one side thereof, said socket having a spring portion intersecting at least one side of said aperture at an angle relative to a line passing through the center of the aperture and the center of the notch.

2. A fastener comprising, in combination, a stud having a head and a neck, and a socket providing a stud-receiving aperture having notches adapted to resist separation of stud and socket by forces resulting from lateral strain, said socket carrying a spring providing oppositely disposed stud-engaging parts adjacent said aperture, said stud-engaging parts intersecting a portion of each of said notches.

3. A stud and socket fastener comprising, in combination, a stud having a head and a neck, and a socket providing a stud-receiving aperture having notches and spring means positioned to cam said stud toward a notch when strain is exerted in a direction generally perpendicular to a line between said notches.

4. A stud and socket fastener comprising, in combination, a stud and a socket, said socket having a stud-receiving aperture narrowed at one end to provide a notch, said notch relatively shallow and opposing separation of stud and socket by forces arising from strain exerted in a lateral direction between stud and socket, and a spring portion in said socket for camming said stud toward said notch when lateral strain is exerted between stud and socket in the general direction of but not directly toward said notch.

In testimony whereof, I have signed my name to this specification.

FRED S. CARR.
